UNITED STATES PATENT OFFICE.

MITCHEL GOULD, OF NEWARK, NEW JERSEY.

IMPROVED GAS-PIPE AND STAIR-ROD.

Specification forming part of Letters Patent No. 43,491, dated July 12, 1864.

To all whom it may concern:

Be it known that I, MITCHEL GOULD, of Newark, in the county of Essex and State of New Jersey, have invented a new and useful Improvement in the Manufacture of Gas-Pipes; and I do hereby declare that the following is full, clear, and exact description thereof, which will enable others skilled in the art to make and use the same, reference being had to the accompanying drawings, making a part of this specification, in which—

Figure 1 is an end sectional elevation of my invention prior to brazing; Fig. 2, a side sectional elevation of the same prior to brazing; Fig. 3, a side elevation of the same prior to brazing; Fig. 4, an end sectional elevation of my improvement completed; Fig. 5, a side sectional elevation of the same completed; Fig. 6, a side elevation of the same completed.

Similar letters of reference indicate like parts.

This invention pertains to the manufacture of that description of tubes which are composed of two sheets or tubes of metal arranged one within the other. The inner tube or sheet is generally made of iron, and the outer tube or sheet of some softer and finer or more ornamental metal. In the present example of my improvement the outer or enveloping tube is composed of brass; but I do not confine myself to the use of any particular kind of metal for either of the tubes.

The usual method of manufacturing these double tubes is first to draw out the inner iron tube and weld it, then draw and braise the brass or enveloping tube to a size just large enough to pass over the iron tube, and then insert the iron tube within the enveloping tube. This is a comparatively slow and expensive method.

In carrying out my improvement I take two

sheets (one of each) of the two metals that I propose to use—say one of iron and one of brass. The outer sheet is cut a little wider than the inner sheet, and the two sheets are now drawn out (by any of the common rolling or drawing devices that are suitable) into tubular form, during which drawing process the softer or enveloping metal is drawn more than the inner metal, and the edges of the enveloping metal are turned or lapped over the edges of the metal comprising the inner tube, as shown in Figs. 1, 2, 3.

A represents the inner sheet or tube of iron; B, the outer or enveloping sheet or tube of brass, and *bb* the edges thereof turned over the edges of the inner tube into the position shown in said figures. The seam or opening *a* in the tube thus drawn is now closed by soldering or brazing the two edges of the enveloping metal at the seam, after which the tube is drawn through a die-plate of smaller diameter, by which drawing the two metals are condensed, solidified, and compressed more firmly together, and a smooth, finished, and strong tube is produced, as shown in Figs. 4, 5, and 6.

The tubes thus made may be employed for conducting gas, or for any other desired purpose to which they are suited.

I do not claim, broadly, the simultaneous drawing of two metals into tubular form; but,

Having thus described my invention, I claim as new and desire to secure by Letters Patent, as an improved article of manufacture—

A tube constructed in the manner substantially as herein shown and described.

MITCHEL GOULD.
